UNITED STATES PATENT OFFICE.

LOUIS FRIEDMAN, OF NEW YORK, N. Y., ASSIGNOR TO FRIEDMAN BROS. & SONS NECK-WEAR CO., INC., OF NEW YORK, N. Y.

BOW TIE.

Application filed September 4, 1923. Serial No. 660,709.

To all whom it may concern:

Be it known that I, LOUIS FRIEDMAN, a citizen of the United States, residing at New York, in the county of New York and State 5 of New York, have invented certain new and useful Improvements in Bow Ties, of which the following is a specification.

This invention relates generally to neckties, having more particular reference to the 10 small neckties generally known as bow ties.

The invention has for an object the provision of a bow tie constructed in a novel manner to give a pleasing appearance and to retain its shape.

15 For further comprehension of the invention, and of the objects and advantages thereof, reference will be had to the following description and accompanying drawing, and to the appended claims in which the 20 various novel features of the invention are more particularly set forth.

Fig. 1 of the drawing is a face view showing my improved bow tie.

Fig. 2 is a fragmentary sectional perspective view showing the strip or strap from 25 which the bow tie is formed, this strip being shown ready for folding to form the tie.

Fig. 3 is a face view partly in longitudinal section.

30 Fig. 4 is a transverse sectional view taken on the line 4—4 of Fig. 3.

In forming my improved tie I take a strip 10 of material of just sufficient length to form the bows of the tie when doubled upon 35 itself. This material may be knitted or woven, and may be silk or any other desired material. This strip of material is first folded, upon opposite sides of its longitudinal median line, over a lining element 11 and the two side edges are secured together 40 as by stitching. The tie is thus left with finished side edges and the two parts thereof are secured together adjacent the side edges by rows of stitching 14 which are run from 45 end to end of the strip. The end portions 10' of the strip 10 are then folded back upon the intermediate portion, forming the front and rear portions of the tie, the ends being stitched together, or secured together in any 50 satisfactory manner. These stitches 14 serve to hold the two elements which are formed by folding the strip 10 longitudinally from sidewise movement with respect to one another, thus assisting in maintaining the 55 proper shape of the tie. The tie is encircled

midway between its ends by the usual cross-piece 16 which holds it crimped to the proper shape and to which the usual neckband 17 is attached.

I may also provide pockets 18 in the wings 60 of the tie between the front and rear portions of the tie formed by doubling the ends of the strip backward as above set forth. To form these pockets the said front and rear portions are secured together by other rows 65 of stitches 19 which are omitted at certain points at the top to leave openings such as indicated at 18'. These pockets may be used to keep rings or like articles concealed. To assist in holding the wing ends of the tie 70 properly extended I may insert, in the said pockets, a loop 20 of a resilient material, such as celluloid, which fits snugly between the two rows 19 of stitches. This loop 20 extends unbroken through the two wings of 75 the tie, being compressed at the centre by the crosspiece 16. It will be understood of course that both the rows of stitches 14 and 19 are not absolutely essential as the single row will suffice to hold all the parts in position. The loop 20 serves an additional function in acting as a closure for the mouths 80 of the pockets in the tie, and as it acts to stretch the material of the tie, it tends to prevent said mouths from accidentally opening. 85

In knitted ties ornamental lines or stripes extending transversely of the tie can be readily woven thereinto but the longitudinal lines which I have shown can only be formed 90 by stitching, and these rows of stitches in addition to their ornamental function act to hold the tie better in shape both as regards transverse displacement of the parts relatively to one another and stretching of the 95 tie in a longitudinal direction.

Having thus described my invention what I claim as new and desire to protect by Letters Patent of the United States is as follows:

1. A bow tie comprising a single length of material having the ends thereof turned back over the intermediate portion, rows of stitching securing the said end and intermediate portions together adjacent their edges, and pockets formed between the end and intermediate portions, said rows of stitching being omitted at certain points along the top edge of the tie to form the mouths of the 100 said pockets. 110

2. A bow tie comprising a single length of material having the ends thereof turned back over the intermediate portion, and pockets formed between the end and intermediate portions, and elements in said pockets acting to hold the tie ends expanded and to close the mouths of said pockets.

3. A bow tie comprising a single length of material having the ends thereof turned back over the intermediate portion, and

pockets formed between the end and intermediate portions, and elements in said pockets acting to hold the tie ends expanded and to close the mouths of said pockets, said elements being formed by a single loop extended from end to end of the tie. 15

In testimony whereof I have affixed my signature.

LOUIS FRIEDMAN.
